UNITED STATES PATENT OFFICE.

JAMES C. ARMSTRONG, OF BELOIT, WISCONSIN.

SANITARY DRINKING-FOUNTAIN.

1,357,436.

Specification of Letters Patent. Patented Nov. 2, 1920.

Application filed March 5, 1920. Serial No. 363,492.

To all whom it may concern:

Be it known that I, JAMES C. ARMSTRONG, a citizen of the United States of America, and a resident of Beloit, county of Rock, 5 and State of Wisconsin, have invented certain new and useful Improvements in Sanitary Drinking-Fountains, of which the following is a specification.

The main objects of this invention are to 10 provide an improved form of sanitary drinking fountain, having an improved form and arrangement of the water supply nozzle, and an improved form of splash-board for preventing the water from splashing over the 15 sides of the bowl.

An illustrative embodiment of this invention is shown in the accompanying drawings, in which—

Figure 1 is a front elevation of the fountain.

Fig. 2 is a side elevation taken from the right of Fig. 1.

Fig. 3 is a longitudinal section taken on the line 3—3 of Fig. 1.

In the form shown, bowl 1 is provided 25 with a drain 3 guarded by a strainer in the form of an inverted cup 4 which is secured to the bowl by a central screw 5. The water jet orifice 6 is located at the front of the bowl and may be flush with the wall thereof. The supply nozzle may be formed by an 30 upwardly inclined bore 7 closed at its lower end by a plug 8. A vertical bore 9 connected with the water supply pipe 10 meets the bore 7 at an angle near the orifice 6. The 35 supply pipe 10 is provided with a suitable valve 11. The peculiar arrangement of the bores 7 and 9 causes the water, which passes therethrough, to form a jet directed rearwardly and upwardly, as indicated by 40 dotted lines in Fig. 3, so that a person may obtain a drink without bringing his lips into contact with anything but the water.

To prevent contamination of the supply 45 nozzle orifice, an inwardly extending guard flange 12 is integrally formed on the front wall of the bowl directly above the orifice 6 where it will be clear of the jet, as shown in Fig. 3. This guard prevents dirt or drip- 50 pings of water from the drinker's mouth from falling into or upon the rim of the orifice 6.

The splash-board 2 which constitutes the 55 back of the fountain, is formed integrally with the bowl and is provided with apertures 13 to receive bolts or other suitable

fastening means for securing the fountain to a wall.

The front face of the splash-board is formed to provide a recess 14 which drains 60 into the bowl and is of sufficient area to cover the range of the jet under various pressures. A wire net screen 15 is secured across the front of the recess 14 so as to break the force of the jet without splashing, 65 and cause the water to be collected and drained into the bowl.

The lower end of the back 2 extends downwardly to form the rear wall of a housing 16 which is integral with the bowl and 70 which communicates therewith through the drain 3. A discharge opening 17 at the rear of the housing connects to the waste pipe 18. A partition 19 extends upwardly from the bottom of the housing and a partition 20 75 projects downwardly from the bottom of the bowl so as to form a trap for water in order to prevent sewer gas from escaping from the waste pipe 18.

When the control valve 11 is open, the jet 80 of water from the nozzle will, under normal conditions, be directed over and into the bowl following a path indicated by the dotted line 19, Fig. 3. If the pressure of the water supply is subject to fluctuation, as 85 is usually the case, the jet will at times of increased pressure, be directed against the back 2 where it will be caught by the screen 15 and prevented from splashing upon the floor. The water which passes through the 90 screen will run down through the chamber 14 into the bowl.

Although but one specific embodiment of this invention has been herein shown and described, it will be understood that numerous details of the construction shown may be altered or omitted without departing from the spirit of this invention as defined by the following claims.

I claim:

1. A drinking fountain comprising a bowl having a splash-board at one side, a nozzle for directing a jet of water above said bowl in the direction of said splash-board, and means on said splash-board adapted to 105 break up a jet of water striking it and prevent the same from splashing over the edges of said bowl.

2. A drinking fountain comprising a bowl having a splash-board at one side, a nozzle for directing a jet of water above said bowl in the direction of said splash-board, and a 110

foraminous wall associated with said splash-board adapted to break up a jet of water striking it and prevent the same from splashing over the edges of said bowl.

5. 3. A drinking fountain comprising a bowl having a splash-board at one side, a nozzle for directing a jet of water above said bowl in the direction of said splash-board, and a wire mesh screen secured across the face of said splash-board whereby a jet of water directed against the splash-board is prevented from splashing over the edges of said bowl.

10 4. A drinking fountain comprising a bowl having a splash-board disposed in a vertical position so as to form the back of said fountain, a water supply nozzle at the forward part of said bowl for directing a jet of water toward said back, the face of said back having a recess therein, and a screen secured across the face of said back, said screen being substantially coextensive with said recess so as to form a broad shallow chamber between said screen and splash-board whereby a jet of water striking the splash-board will be collected and conducted into said bowl without splashing.

15 5. A drinking fountain comprising a bowl having a drain formed in the bottom thereof, a splash-board on said bowl and forming the back of said fountain, a nozzle in the forward part of said bowl for directing a jet of water upwardly and in the direction of said back, a screen secured in front of said back whereby the water directed 20 against said back is prevented from splashing over the edges of said bowl, and a depending housing integrally formed on the bottom of said bowl and communicating at one end with said bowl through said drain, 25 said housing having a discharge outlet located at the opposite end thereof, and a pair of vertically disposed partitions mounted in spaced relation between said drain and outlet opening, one of said partitions extending 30 downwardly from said bowl, the other of said partitions extending upwardly from the bottom of said housing so as to form a trap for the water passing through said drain.

35 Signed at Chicago this 3rd day of March, 1920.

JAMES C. ARMSTRONG.
